UNITED STATES PATENT OFFICE.

WESLEY A. PAUL, DECEASED, LATE OF MOLINE, ILLINOIS, BY LOLA V. PAUL, ADMINISTRATRIX, OF MOLINE, ILLINOIS, ASSIGNOR TO DEERE & COMPANY, OF MOLINE, ILLINOIS, A CORPORATION OF ILLINOIS.

CLEVIS.

1,243,972.

Specification of Letters Patent. Patented Oct. 23, 1917.

Application filed January 6, 1915, Serial No. 860. Renewed April 27, 1917. Serial No. 164,996.

To all whom it may concern:

Be it known that WESLEY A. PAUL, late a citizen of the United States, and a resident of Moline, in the county of Rock Island and

- 5 State of Illinois, did invent certain new and useful Improvements in Clevises, of which the following is a specification, reference being had therein to the accompanying drawing.
- 10 My invention relates to clevises, preferably for use on agricultural implements or machines, particularly upon plows of various types, and the object of my invention is to form such clevises from sheet metal, as 15 distinguished from the common type manufactured from cast metal.

Figure 1 shows a blank cut from a sheet of metal.

Fig. 2 is a plan view of Fig. 1.

- 20 Fig. 3 is a plan view of the completed clevis.

Fig. 4 is a side view of Fig. 3.

Fig. 5 illustrates a modification of my invention.

- 25 In manufacturing my clevis a blank of sheet metal, of the required size and thickness, is subjected to the action of a suitable machine, preferably a power press, by which the perforations 2, 3, 4 and 5 are 30 made and at the same time a portion of one edge of the blank is cut away forming the recess 6; simultaneously with the operation just described, a slot 7 is cut in the blank parallel with the upper edge thereof, the 35 metal being cut on three sides only and bent outwardly on the remaining side to form the flange 8, substantially at right angles to the face of the blank 1.

- The slot 7 in the completed article forms 40 a recess adapted to receive a connection, such as a link by which the clevis is attached to the desired implement, the two being adapted to be held in engagement by a clevis pin in the sleeve 9, the clevis pin being 45 shown in position in dotted lines in Fig. 4, the formation of said sleeve being more fully hereinafter described. The flange 8 forms a support on the connection keeping the clevis in a position substantially at right 50 angles thereto.

I then bend the blank 1 on a central vertical line without altering the position of the flange 8, which remains at right angles to the face of the blank.

During the above described operation the 55 sleeve 9 is formed for the reception of a clevis pin. The two sides, 10 and 11, of the blank 1 are brought, for a portion of their length, into parallel relation, the holes 3 and 4 registering and a bolt or rivet 12 60 placed therein, holding the sides 10 and 11 together. The sides 10 and 11 diverge at an angle for an equal distance from their parallel portions and are then brought into spaced parallel relationship for the remainder of their lengths, the perforations 2 and 5 coming opposite each other to permit a hitch pin being placed therein. By means of the holes 2 and 5, a hitch may be made at any desired position on the clevis. 70

In manufacturing the modification of my invention, as illustrated by Fig. 5, the operation is the same as heretofore described, with the exception the sides 10 and 11, of the blank 1, continue in close parallel relation for their entire length. 75

My device is economical in construction and is much stronger and more desirable than a cast clevis.

What I claim is:—

80 A clevis formed from a blank of sheet metal, the blank being bent upon itself at a central vertical line and forming a sleeve at the bend, a slot extending laterally of said sleeve and having a flange on one edge 85 parallel with the slot, and perforations in the blank on each side of the central vertical line, the perforations on one side adapted to register with the perforations on the opposite side when the blank is bent. 90

In testimony whereof I affix my signature, in presence of two witnesses.

LOLA V. PAUL,

Administratrix of the estate of Wesley A. Paul, deceased.

Witnesses:

JESSIE SIMSER,
W. G. DUFFIELD.
